SEWING MACHINE

Emil Prazak, Elizabeth, N. J.

Substitute for application Serial No. 680,166,
July 13, 1933. This application December 3,
1935, Serial No. 52,653

2 Claims. (Cl. 112—158)

This invention relates to improvements in sewing machines adapted to effect in operation predetermined pattern stitching; this application being a substitute for applicant's prior application 5 Serial No. 680,166, filed July 13th, 1933.

The invention has for its principal object to provide a novel construction of sewing machine having improved means for varying the stitch formation so as to produce pattern effects upon 10 the material sewn, such, for example, as "dotted swiss" effects and various other design effects. To this end the machine comprises a novel adjustable means for automatically varying the feed of material sewn upon, in combination with means 15 for automatically varying the needle bar operation of the machine to produce groups of straight run or longitudinal stitches formed under normal or maximum feed conditions, alternated with groups of substantially laterally extending 20 stitches, formed under reduced feed conditions; the arrangement of feed variation control being such that the amplitude of reduced feed is subject to quick and easy adjustment within the range of the amplitude of the normal feed for 25 straight run stitches, thus permitting a considerable range of variation of lateral stitch spacing, with consequent variation or modification of produced pattern or design effects.

Other objects of this invention, not at this time 30 more particularly enumerated, will be apparent in the following detailed description of the invention.

An illustrative embodiment of the invention is shown in the accompanying drawings, in which: 35 Fig. 1 discloses a vertical longitudinal sectional view of the machine equipped with improvements according to this invention, certain parts being shown in side elevation; Fig. 2 is a horizontal sectional view, taken partially in the plane of the 40 drive shaft and partially in the plane of the feeder means of the machine; Fig. 3 is a fragmentary vertical longitudinal section, taken on line 3—3 in Fig. 2; Fig. 4 is a fragmentary transverse vertical section, taken on line 4—4 in Fig. 1, and drawn on an enlarged scale, the associated eccentric actuated connecting rod being omitted, this view 45 showing the feed control means operative for reduced feed operation; Fig. 5 is a view similar to that of Fig. 4, but showing the feed control means operative for normal or maximum feed operation; Figs. 6, 7 and 8 respectively show various 50 illustrative examples of pattern effects attained by the improved sewing machine of this invention.

Similar characters of reference are employed

in the above described views, to indicate corresponding parts.

Referring to the drawings, reference character 10 indicates the base of a sewing machine having an upstanding pedestal 11 from which projects 5 the arm 12, which is spaced above and which overhangs base 10. At the free end of arm 12 is the vertically disposed head 13.

Journalized in arm 12, so as to extend longitudinally therein, is a drive shaft 14. Pivotedly connected at 15 with the upper end of head 13 is a dependent oscillatable needle-bar guide frame 16, which slidably supports a vertically reciprocal needle-bar 17 equipped at its lower end with the usual sewing needle 18. Needle-bar 17 is reciprocated by the usual crank transmission 19 which is actuated by drive shaft 14. Fixed on drive shaft 14 is a sprocket wheel 20 which drives, through belt 21, a sprocket wheel 22 of shaft 23 journaled to extend beneath base 10 and which 20 actuates the rotary shuttle (not shown) of the machine sewing mechanism.

Supported by head 13 is the usual vertically yieldable presser foot 24 which cooperates with the feed-dog means 25 by which the material sewn 25 is controlled and advanced relative to the sewing mechanism. The operative movement of feed-dog means 25 comprises a compound of rising and falling or vertically reciprocal movement and forward and back or horizontally reciprocal movement. The vertically reciprocal movement, which brings the feed-dog means into and out of operative contact with material sewn, is effected through oscillation of a rock-shaft 26, the oscillations of which are produced by an eccentric 35 27 operatively connected thereto by connecting rod 28. Said eccentric 27 is nonadjustable as to stroke or throw. The horizontally reciprocal movement, which causes the feed-dog to advance the material sewn in the formation of each stitch, 40 is effected through oscillation of a rock-shaft 29, the oscillations of which are produced by an eccentric 30, operatively connected thereto by connecting rod 31. Said eccentric 30 is adjustable to vary its effective stroke or throw under certain 45 conditions.

The means whereby eccentric 30 is rendered adjustable to vary its effective stroke or throw, and thus alter the amplitude of material feed movement of feed-dog means 25 comprises a frame 32 50 of which eccentric 30 is a part. This frame 32 is provided at its underside with an arm 33 pivotally secured, by pivot means 34, to the face of sprocket wheel 20, so that the frame and eccentric 30 may be moved relative to axis of drive 55

shaft 14 by which the frame and eccentric is rotated through its connection with sprocket wheel 20. At its upper side, frame 32 is provided with a lug 35 having a slot 36 concentric to the axis of pivot means 34. Fixed on the adjacent face of said sprocket 20 is a stud 36' which projects into said slot 36. Into one side of said lug 35 is threaded an adjustable stop-screw 37 which enters an end of said slot 36. Threaded downwardly through the end of said lug 35 is a set-screw 38, which can be tightened down into binding relation to said stop-screw 37, to thereby secure the latter against displacement from any selected operative position to which it has been adjusted. The frame 32 and eccentric 30 carried thereby are provided with an opening 39 of greater diameter than that of the drive-shaft 14, and through which the latter extends. At one side of frame 32 is provided a laterally extending arm 40 having a tubular bore 41 extending longitudinally therethrough. Arranged in the bore 41 is a compression spring 42, the outer end of which is backed by a seating screw 43 which is threaded into the outer end of bore 41. The inner end of spring 42 yieldably thrusts against the side of drive shaft 14. At the opposite side of frame 32 is an oppositely and laterally extending arm 44 having an internally screw-threaded bore 45. Threaded into bore 45 is the threaded base 46 of a thrust pin 47, the latter extending through the frame opening 39 and through the side of drive-shaft 14, with its free end disposed within a hollow tubular interior or bore 48 with which said drive-shaft 14 is provided. Slidable in the interior or bore 48 of said drive-shaft 14 is a plunger 49 having at its inner end a conical cam-portion 50. The outer end of said plunger 49 projects exteriorly from the end of said drive-shaft 14. When said plunger is slid or pushed inwardly, its conical cam-portion 50 is moved against the thrust pin 47, thereby pushing the same outwardly, and thus swinging frame 32 and its eccentric 30 about the pivotal connection 34, against the compression of spring 42, to carry the eccentric 30 to maximum offset relation to the axis of drive-shaft 14, i. e. to its normal maximum eccentric stroke or throw, under which conditions the straight run or longitudinal stitches are produced. When said plunger 49 is retracted to free thrust pin 47 from the engagement thereof, spring 42 exerts its thrust upon frame 32 to swing the same in the opposite direction until stopped by the engagement of stop-screw 37 with the fixed stud 36', thereby disposing the eccentric 30 in minimum offset relation to axis of drive-shaft 14, i. e. for predetermined minimum eccentric stroke or throw, under which conditions the substantially lateral stitches are produced.

The means for producing lateral oscillations of the vertically reciprocated needle-bar 17 and its needle 18 to produce the substantially lateral stitches under reduced or minimum material feed conditions, whereby the desired stitched pattern or design effects are produced on the material sewn, comprises a rotary cam wheel 51, shaft or spindle 52 of which is transversely journaled in the arm 12. Said shaft or spindle 52 is actuated by a worm-gear 53 fixed on its inner end portion and adapted to be driven by a worm 54 fixed on drive-shaft 14. Cam wheel 51 is provided in its face with a suitably shaped cam groove or race 55. Pivotally mounted on a bracket 56 associated with arm 12 is a lever member, the upwardly extending arm 57 of which is provided with a roller stud 58 operatively engaged in said cam groove

or race 55. To the downwardly extending arm 59 of said lever member is adjustably connected one end of a connecting rod 60, the opposite or outer end of which is pivotally connected with the needle-bar guide frame 16. The cam groove or race 55 is shaped throughout a portion of its length to provide a race-portion concentric to the axis of said cam wheel, whereby, when such portion engages roller stud 58, the lever member 57-59 is held stationary, to in turn hold the needle-bar guide frame 16 stationary in perpendicular position when straight run or longitudinal stitches are being formed; the remaining portion of said cam groove or race 55 is of waving formation, whereby, when such portion engages roller stud 58, lever member 57-59 is oscillated to in turn swing laterally back and forth the needle-bar guide frame 16 to produce the substantially lateral stitches. Cam wheel 51 is further provided in its face with a second cam groove or race 61. Pivotally mounted on the pedestal 11 is a rocking arm 62 provided with a roller stud 63 to engage in said cam groove or race 61. Said rocking arm 62 is connected by link 64 with a second rocking arm 65 which is fulcrumed by a rock-shaft 66 journaled in a bracket 67 attached to said pedestal 11. Fixed on said rock-shaft 66 is a push-lever 68, the free oscillatable end of which is opposed to the outer end of said plunger 49. Said plunger carries at its outer end a diametrically enlarged end-piece 69, which is outwardly thrust by means of a compression spring 70 to dispose said plunger 49 in retracted position. Cam groove or race 61 is shaped to provide an outer concentric portion and an inner concentric portion, the latter being operatively engaged by roller stud 63 to swing inwardly the plunger control means so as to hold plunger 49 inwardly thrust to in turn hold eccentric 30 in maximum throw position so as to actuate the feed means 40 at major amplitude during the production of straight run or longitudinal stitches; and the outer concentric portion of cam race 61 operatively engages roller stud 63 to swing outwardly the plunger control means so as to permit plunger 49 to be retracted, to in turn hold eccentric 30 in minimum or reduced throw position whereby the feed means is actuated at minor amplitude during the production of the substantially lateral stitches.

From the above description it will be obvious that, by the operation of the machine, a pattern or design stitching may be sewn onto material, which stitching comprises alternated straight run stitches and groups of laterally disposed stitches, the stitches of the latter groups being comparatively closely spaced together by means of the reduced operative amplitude of the material feed means which automatically occurs when such stitching is sewn. In this manner patterns or designs with various dotted effects may be obtained. The lateral stitches may be closely spaced by setting the stop screw 37, so as to reduce the throw of eccentric 30 to an amplitude which will feed the material sewn but for a distance approximating the width of the thread employed, in which case the lateral stitches will form a more or less solid dot-like formation of embroidered appearance, such, for example, as shown in Figs. 6 and 8. On the other hand, the stop-screw 37 may be adjusted to stop the frame 32 and dispose the eccentric 30 in any selected position within the range of its maximum-minimum throw, in which case the lateral stitches may be disposed to form more or less open zig-zag

patterns, such, for example, as shown in Fig. 7. The peripheral shape of the lateral stitch produced dots or design patterns, is effected by the specific character of the waved portion of cam race 55. For example, said cam race portion may be shaped to progressively increase and then decrease the lateral oscillatory movement of the needle bar 17 and needle 18, thus producing dots or design patterns of diamond-like outline, as shown in Fig. 6; or said cam race portion may be shaped to produce uniform oscillatory movement adapted to produce dots or design patterns of more or less rectangular outline, as shown in Fig. 8. It will be obvious that other outline shapes may also be produced by suitably varying the shape of the waved portion of cam race 55.

Having thus described my invention, I claim:

1. In a sewing machine having a vertically reciprocable and transversely oscillatable needle and cooperating feed means, mechanism for actuating said feed means for both maximum and minimum amplitude of feeding movement comprising, a drive shaft, a frame having a feed operating eccentric, carrier means rotated by said shaft to which said frame is pivoted for lateral movement relative to said shaft, the free end of said frame having a slot, a fixed stud on said carrier

means entered in said slot, spring means urging said frame in one direction in stopped engagement with said stud to thereby position the eccentric for minimum throw adapted to effect minimum amplitude of feed means movement, means to move said frame in an opposite direction and hold the same against the tension of said spring to position the eccentric for maximum throw adapted to effect maximum amplitude of feed means movement, and adjustable means for varying the stud stopped position of said frame and eccentric to selectively predetermine the scope of minimum amplitude of feed means movement, said latter means comprising an adjustable stop screw carried by said frame to enter an end of its slot in opposition to said stud.

2. In a sewing machine having mechanism as defined in claim 1, wherein the means to move said frame to dispose said eccentric in maximum throw position comprises a plunger slidable in said drive shaft, a thrust pin carried by said frame and engageable by said plunger, oscillatable lever mechanism for actuating said plunger, a rotary control cam to effect timed movements of said lever mechanism, and drive shaft operated transmission for actuating said cam.

EMIL PRAZAK.
